UNITED STATES PATENT OFFICE.

HENRY W. PLEISTER, OF WESTFIELD, NEW JERSEY, ASSIGNOR TO HENRY B. NEWHALL.

BOLT ANCHOR.

Application filed September 23, 1921. Serial No. 502,766.

To all whom it may concern:

Be it known that I, HENRY W. PLEISTER, a citizen of the United States, residing at Westfield, in the county of Union and State 5 of New Jersey, have made certain new and useful Improvements in Bolt Anchors, of which the following is a specification, taken in connection with the accompanying drawings.

10 My invention relates to bolt anchors or expansion bolts, and more particularly to what is known in the trade as machine expansions.

15 My invention relates more particularly to forming the shell or shells of the expansion from rolled pressed steel of minimum thickness for the particular size expansion.

20 My invention further relates to using this pressed steel shell or shells in combination with the ordinary malleable iron nut and collar, or preferably in combination with a steel nut, or steel collar, or both, my invention comprising any combination of these different elements as set forth in the claims.

25 My invention further relates to certain combinations, sub-combinations, articles of manufacture, and details of constructions all of which will be more fully hereinafter described and pointed out in the claims.

30 In the drawings I have shown different embodiments of my invention but it is of course to be understood that my invention is not to be confined to the embodiments shown by way of illustration.

35 Fig. 1 is a vertical section showing my pressed steel shell used in combination with a malleable iron collar and malleable iron nut;

Fig. 2 is a view similar to Fig. 1 but 40 showing the parts after they have been expanded within the wall or other suitable support;

Fig. 3 is a vertical section on the line 3—3 of Fig. 1;

45 Fig. 4 is a vertical section on the line 4—4 of Fig. 1;

Fig. 5 is a plan view of the blank;

Fig. 6 is a cross-section of the blank on the line 6—6 of Fig. 5;

50 Fig. 7 is a perspective view of one of the units after being bent or shaped to form a substantially semi-circular shell;

Fig. 8 is a perspective view of the malleable iron collar used in Fig. 1;

55 Fig. 9 is a vertical section through a modi-

fied and preferred form of collar formed from steel tubing one end of which has been expanded;

Fig. 10 is a vertical section through a modified form of steel nut formed from tubing one end of which has been expanded;

Fig. 11 is a perspective view of a spring ring which I may employ to hold the shells together;

Fig. 12 is a fragmentary detail view of a modified form of construction in which the end of the lugs are upset so as to secure the shells to the collar and nut;

Fig. 13 is a vertical detail section, similar to Fig. 12, showing the lugs of the pressed steel collar and nut upset for the same purpose.

Expansion bolts and more particularly machine expansion bolts are now commonly made from castings of malleable iron. 75 There are many objections, however, in manufacturing them in this manner. The cost is relatively high for there are limits in the thinness of the walls that can be cast from malleable iron so that the resulting casting is heavier than necessary in places where thickness is not required. Moreover in the ordinary manufacture of machine expansions formed of malleable iron castings, there is a large waste from warping of the 80 castings, mis-runs, too thin castings, sand holes, blow-holes, rough surfaces, fins, and other deformities. Also considerable grinding has to be done in removing sprues from the malleable iron castings, all of which add 85 greatly to the expense of manufacture.

By my invention I avoid all this waste and expense, obviate grinding and rejections or discards by forming a finished uniform product which can be turned out from the 95 press without any further work except in connection with the pressed steel nuts, when used, which have to be screw-threaded. The resulting product by my method takes only the minimum amount of metal for the required expansion.

In the embodiment of my invention shown in the drawings, 1 is a blank of pressed sheet steel of the required minimum thickness for the particular expansion to be manufactured. 105 This blank is provided in any suitable manner, as for example by rolling, with bevel edges 2, 2 and is of a width to correspond with the length of the shell of the expansion to be manufactured. This blank is fed 110

through a punch press which divides the blank into units 8, 8 on the line 3, 3, preferably also punching out the V-shaped slots 4, 4 between each unit. At the same time I 5 preferably punch the elongated slots 5 and 6 on the central axis of each unit. I also preferably, though not necessarily, punch at the same time a hole 7 in each unit.

The units 8, 8 are then fed into a forming 10 die which will roll them or shape them into semi-cylindrical shells 9, 9, Fig. 7. In the form of my invention illustrated two of these shells 9 are employed, and preferably, though not necessarily, secured together by means of the spring ring 10, Fig.

11. This ring is provided with a crimp 11 and its ends are provided with fingers 12, 12. In positioning the ring the crimp 11 will be positioned in one hole 7 in one shell 20 9 and the fingers 12, 12 will be positioned in the corresponding hole 7 in the other shell 9, as shown more clearly in Fig. 4.

The bevel surfaces 2, 2 form the inclined 25 surfaces 2, 2 of the shell 9 so that each shell is thicker intermediate its length than it is at its ends.

I may use any suitable means to expand the shells 9, 9. For example, as shown in Figs. 1 and 2, I may employ a malleable 30 iron collar 13 and a malleable iron nut 14. The malleable iron collar 13 is provided with lugs 15, 15 which are received in, and cooperate with, the elongated slots 6, 6 in the shells 9, 9. The lugs 15, 15, Figs. 1 and 35 2, on the malleable iron nut 14 are received in and cooperate with the elongated slots 5, 5 in the shells 9, 9.

In positioning the work 16, the bolt 17 is passed through the work, the unthreaded 40 malleable iron collar 13 and through the malleable iron nut 14, which is provided with screw-threads to cooperate with those on the bolt 17. By turning the head 18 of the bolt the shells 9, 9 are caused to expand 45 in parallel relation to each other, as shown in Fig. 2.

In this form of my invention I use 50 pressed steel shells 9, 9 with a malleable iron collar and a malleable iron nut. Preferably, however, I use a pressed steel collar and a pressed steel nut with my pressed steel shells 9. I have shown in Fig. 9 a pressed steel collar 19 formed of tubing of the required diameter for the particular 55 size expansion, one end being expanded in any suitable manner, to form a frustum of a cone 20. Preferably, I cut the unexpanded portion 21 and bend out the cut metal to form the lugs 22, 22.

60 My present steel nut 23, Fig. 10, is likewise provided with an unexpanded portion 24 and an expanded portion 25 forming a frustum of a cone. The unexpanded portion is cut and provided with lugs 26, 26. 65 Unlike the collar 19, the nut is provided

with screw-threads 27, to cooperate with the threads upon the bolt 17. I may use with the pressed steel shells 9, 9 both the pressed steel collar and nut 19 and 23, or I may substitute for either or both the 70 collar and nut, one of malleable iron collars or malleable iron nuts.

In some cases I dispense with the ring 10. I may for example, as shown in Fig. 12 upset the lugs 15, 15 forming upon them 75 heads 28 sufficiently large to prevent the disengagement of the shells 9, 9, it being understood that the lugs on the malleable iron nut are upset in the same manner.

In Fig. 13 I have shown the lugs 22 upset for the same purpose of preventing the disengagement of the parts one from the other without the aid of the spring ring 10.

Having thus described this invention in connection with illustrative embodiments thereof, to the details of which I do not desire to be limited, what is claimed as new and what is desired to secure by Letters Patent is set forth in the appended claims.

What I claim is:—

1. The combination in an expansion bolt of expansible shells, a collar, a nut, and cooperating means between the shells, collar and nut and integral with the collar 95 and nut to secure them together.

2. The combination in an expansion bolt of expansible shells provided with slots, a collar and a nut, lugs on the collar and nut cooperating with the slots in the shells, and integral means on the lugs to prevent the 100 disengagement of the parts.

3. The combination in an expansion bolt of expansible shells provided with slots, a collar and a nut, lugs on the collar and nut cooperating with the slots in the shells, the ends of the lugs being upset to prevent 105 disengagement of the parts.

4. The combination in an expansion bolt of a plurality of pressed steel shells having inclined surfaces at each end, and elongated slots, an expanded steel collar and an expanded steel nut, the collar and nut being provided with lugs to cooperate with the elongated slots in the steel shells.

5. The combination in an expansion bolt of a plurality of pressed steel shells having inclined surfaces at each end, and elongated slots, an expanded steel collar and an expanded steel nut, the collar and nut 120 being provided with lugs to cooperate with the elongated slots in the steel shells the ends of the lugs being upset to prevent disengagement of the shells from the collar and nut.

HENRY W. PLEISTER.
